ANIMATED TOY MONKEY

Frank Stanton, 1 W. 72nd St., New York, N.Y.

Filed May 4, 1962, Ser. No. 69,984

Term of patent 14 years

(Cl. D34—15)

I claim:

The ornamental design for an animated toy monkey, as shown.
